WRAPPING MACHINE

Phillip Cravits, Burbank, Calif.

Application December 24, 1951, Serial No. 263,032

11 Claims. (Cl. 53—378)

This invention relates to the packaging art and particularly to a machine for wrapping various articles. Specifically, the invention pertains to a machine for applying protective coverings or wrappers to boxes or small packages in which various articles are packed for shipment or display purposes.

The present improved package wrapping machine has particular utility when employed for applying flexible, plastic wrappers to rectangular boxes, for example, for enclosing cardboard boxes in a protective wrapper or enclosure of a transparent, foldable, fusible, cellulose material such as that sold under the trade name "Cellophane," and in the following specification the machine is described in this connection, by way of example.

In the packaging art it is common to enclose boxes and like containers in transparent wrappers so as to effectively protect the boxes to minimize damage thereto and soiling thereof, in some instances the wrapper providing a moisture impervious seal for protecting the contents of the boxes. Such wrappers are usually applied to the boxes in wrapping machines which are specially designed for the purpose. Conventional wrapping machines usually involve quite complicated mechanisms for feeding the boxes and for cutting the wrapper material to the required size, folding the material against the boxes and sealing the material. Such machines commonly employ movable tucking and folding elements and since it is difficult to design such machines to provide adjustability so as to accommodate packages of different sizes, it is customary to construct machines which are capable of wrapping only a box of predetermined height. For this reason, it is not unusual to employ a large number of wrapping machines, each adapted to operate on boxes of a particular size, in a plant where packages of various sizes are produced and filled for shipment. While it is within the realm of possibility to so construct such machines to provide adjustability and thus make it possible to wrap boxes of various sizes, within limits, in a single machine, the cost of producing such machines has heretofore been considered prohibitive and consequently the packaging methods and machines discussed above have been 55 tolerated.

It is an important object of the present invention to obviate the deficiencies of previous wrapping machines by providing a machine of this character which is particularly adapted to apply wrappers to rectangular boxes or like containers of various sizes, within prescribed limits, the improved machine being so constructed that a single, relatively simple adjustment prepares the machine for operating upon boxes of a selected size. In this respect, the highly advantageous result is attained by providing a machine which embodies a series of tucking and folding elements, each of which is so formed and arranged as to tuck or fold a different flap of the wrapper upon relative movement between the package and the particular elements involved, an important object of the invention being to provide a machine in which the various

2

tucking and folding elements remain stationary, with respect to the package being wrapped, so as to greatly simplify the machine, and this is another object of the invention.

Another important object of the invention is to provide a machine of the type indicated in which the package to be wrapped is fed along a support or bed relative to the stationary folding means to effect folding of the flaps at the opposite ends of the wrapper. In the present machine, the package, together with its encircling wrapper, is disposed with its length extending transversely of the support and with the flaps of the wrapper to be folded disposed at opposite longitudinal sides of the support, the package and its wrapper being moved in this position successively to the various folding means, and this is another object of the invention.

Another object is to provide a machine, of the class referred to, in which the longitudinal support is made in two transversely spaced parts, each part being in the form of a rail upon which an end of the package rests and along which the package is advanced to the successive folding elements. A further important object in this respect is to provide means for adjusting the rails toward and away from each other in accordance with the length of the box or other package to be wrapped, the adjusting means consisting simply of manually rotatable screws engaging the rails and operative to spread the rails apart or draw them closer together, depending upon the direction of rotation of the screws.

Another object is to provide a machine of the type specified in which the means for folding the projecting ends of the wrapper comprises a pair of primary tucker elements which function to tuck the rearward vertical portion of the wrapper laterally inwardly against the ends of the package, a pair of secondary tucker elements which are operative to tuck the forward vertical portions of the projecting wrapper ends laterally inwardly against the ends of the package, a pair of primary folder elements which are adapted to fold the upper horizontal portions of the projecting wrapper ends downwardly in overlying relation to the previously tucked portions, and a pair of secondary folder means which effect upward folding of the lower horizontal portions of the projecting wrapper ends in overlying relation to the aforesaid tucked and folded portions, the machine further including heater elements operative to seal the overlying end portions to effect a moisture impervious protective covering.

In accordance with the present invention, the primary tucker means comprises a pair of transversely spaced slide elements, which are reciprocable along the support rails as a unit, suitable motor operated means being provided for effecting reciprocation of the same, this being a feature of the invention. A related object is to provide primary tucker means in which each tucker element has a plurality of forwardly projecting fingers, the fingers of the elements being spaced apart a distance equal substantially to the length of the package being wrapped so that when the package is slid into position between the fingers, the rearward vertical portions of the projecting wrapper ends are automatically tucked against the ends of the package. The primary tucker elements have rearward pusher portions which serve to push the package forwardly to the secondary tucker elements.

The secondary tucker elements consist of a plurality of vertically spaced, stationary bars extending longitudinally along the sides of the support, the ends of the bars directed opposite to the path of feeding movement of the package being rounded and adapted to engage and tuck the forward portions of the wrapper ends inwardly against the ends of the package, the remaining lengths of the bars serving to retain both tucked portions of the

wrapper against the package which is advanced by the primary tucker means to a point adjacent said secondary tucker elements, the form of the secondary tucker elements also being a feature and object of this invention.

Another important object of the invention resides in the primary and secondary folder means, the former being merely a plurality of vertically spaced bars, the package being adapted to move forwardly between the series of bars, each bar of the series having a lower inclined folder edge which slopes downwardly in the direction of feed of the package, the upper horizontal portions or flaps of the wrapper ends being adapted to engage one or another of these inclined edges and to be folded downwardly thereby during forward motion of the package along the support. As an important feature, the rearward upper ends of the inclined folder edges of the uppermost bars are disposed at a considerable height above the support while the forward lower ends of the folder edges are located at the approximate level of the top of the support. By this provision, packages having wide ranges of heights can be operated upon, the maximum height being limited only by the distance of the upper end of the uppermost bar above the support.

Another object is to provide secondary folding means which is simple in construction and positive in action. The secondary folding means consists of a pair of transversely spaced, pivoted, plate-like elements each having an edge which slopes upwardly and forwardly in the direction of travel of the package, the lower end of the inclined edge being normally disposed at a level which is preferably slightly below the level of the top of the support so that as the package advances, the lower flaps of the wrapper ends engage and are folded upwardly against the previously folded upper flaps thereof. Another object in this respect is to provide means for heat sealing the several flaps or folds of the wrapper ends, this means consisting in heater plates across which the folded ends of the wrapper travel to cause the flaps thereof to be fused together.

It is an additional object and feature of this invention to provide auxiliary folder means for folding the upper and lower flaps of the wrapper ends against the bottom of the package, this means consisting in a pair of bottom fold slots in the upper surface of the support, these slots extending inwardly and forwardly from points adjacent the bottom portions of the inclined edges of the pivoted secondary folder elements. By this provision, when the secondary folder elements are pivoted to a position in which their inclined edges are disposed out of the path of travel of the bottom flaps and are thus rendered inoperative, the bottom flaps are deflected downwardly by the primary folding means into the bottom fold slots and the lower ends of the folded upper flaps are also caused to enter these slots. During the forward movement of the package the upper and lower flaps are simultaneously folded under the ends of the package by the forward edges of the bottom fold slots. This is an important feature of the invention since it provides means by which sealing of the upper and lower flaps can occur at the bottom of the package and this is highly desirable when wrapping, for example, ornamental candy boxes and like containers in which the edges of the top and bottom project outwardly beyond the intermediate main box portion and thus make it impractical to heat seal the wrapper against the ends of the box.

It is a further object to provide means for positively feeding the boxes successively to the tucking and folding means. As indicated in the foregoing, the primary tucker means also serves as a primary feeding means for advancing each package to the secondary tucker means. The invention provides additional or secondary package advancing means operative to feed the package through the remainder of its necessary travel. The primary and secondary feeding means are reciprocated in timed sequence so that during the feeding of a package

from its initial loading position to the secondary tucker means, another package, which was previously so fed by the primary feeding means, is advanced by the secondary feeding means to complete its travel through the machine.

- 5 In the present improved machine the feeding means engages only the rearward side of the package to push the same forwardly so that damage to or displacement of the partly applied wrapper is entirely avoided, and this is another object of the invention.
- 10 Further objects of the invention will appear from the following description and from the drawings, which are intended for the purpose of illustration only, and in which:

15 Fig. 1 is a side elevational view of the improved wrapping machine, the components of the machine being shown at the start of a wrapping operation;

Fig. 2 is a cross-sectional view, taken on line 2—2 of Fig. 1;

Fig. 3 is a fragmentary plan view of the tucking and folding elements;

20 Figs. 4, 5, 6, 7 and 8 are fragmentary side views of the tucking and folding elements, showing the progressive movement of a package to be wrapped through the machine and illustrating the manner in which the end flaps of a wrapper are tucked and folded;

Fig. 9 is a cross-sectional view, taken on line 9—9 of Fig. 8;

Fig. 10 is a perspective view of a wrapped container, the ends of the wrapper material having been folded against the ends of the container; and

30 Fig. 11 is a perspective view of a wrapped container, illustrating the manner in which the top and bottom flaps of the wrapper ends may be folded under the bottom of the container to provide a bottom fold.

35 Referring to the drawings in detail, the present improved wrapping machine is intended for use in applying a sheet 15 of flexible wrapping material to the exterior of a cardboard box or similar container 16 into which various articles may be placed for storage or shipment.

40 As is customary in the packaging art, the sheet of wrapping material is cut slightly wider than the girth of the box to be wrapped so that the side edges of the sheet overlap to a slight extent, these edges being suitably secured together or to the bottom surface of the box.

45 The ends of the wrapper project beyond the ends of the box, the side, top and bottom portions of the wrapper ends being usually folded in the manner shown in Fig. 10 to provide overlapping rearward and forward flaps 17 and 18 respectively, a top flap 19 and a bottom flap 20.

50 The various flaps are folded against the ends of the box in the order named and secured in this relationship by a suitable adhesive material, a gummed tape or, when the wrapper material is of a fusible nature, by heat sealing the flaps. The present invention is concerned primarily

55 with means for folding the flaps of the wrapper against the box or other container and not to the means for securing the flaps in their folded condition, which may be of any type capable of acting automatically on the flaps prior to discharge of the wrapped packages from the machine.

60 Referring to Figs. 1, 2 and 3 of the drawings, the present machine includes a rectangular standard or frame 25 which has an upper horizontal bar 26 composed of a pair of vertically spaced angle irons 27 and 28. The upper edge of the lower angle iron 28 provides a longitudinally extending track 29.

65 A second frame 30, similar to the frame 25, is disposed alongside the latter in spaced relation thereto (Fig. 2) and has an angle iron 31 at its upper end. Secured to the angle irons 31 and 27 at one end and extending transversely thereof is a stationary tube 32. Adapted to slide within the tube 32 is a second tube 33. The stationary tube 32 extends through aligned apertures in the depending side walls 34 of a first longitudinally extending support rail 35, the tube 32 being suitably secured 70 to the first support rail, which has an upper wall 36. The

75

slidable tube 33 is similarly joined to the side walls 37 of a second longitudinally extending support rail 38 having a top wall 39, the tube 33 having a flange 40 at one end abutting the outer wall 37 of the rail 38. Attached to the other end of the tube 33 is the flange 43 of a sleeve 44 which is disposed within the tube 33. The sleeve 44 has an internally threaded plug 45 at its inner end and screwed into the plug is an adjusting screw 46 which projects through the flange 40 and carries a handwheel 47. Adjacent the opposite end of the machine the rail 35 is connected to a fixed tube which is similar to the tube 32, and the rail 38 is carried by a tube which is similar to the tube 33 and which is slideable in the fixed tube, the outer flange 48 of the slideable tube being indicated in Fig. 1.

It will be apparent from the foregoing that when the handwheel 47 and screw 46 are rotated, the support rail 38 is moved transversely toward or away from the stationary rail 35, depending upon the direction of rotation of the screw, so as to adjust the support rails relatively toward or away from each other for a purpose to be later explained.

Each support rail 35 and 38 carries a sheet metal guide element 50 which is substantially channel-shaped in cross section, each element having inwardly directed flanges 51 defining a guideway or track therebetween in which a roller 52 is adapted to roll. The rollers 52 are rotatable on vertical axes on bars 53 which extend between a pair of tubular members 54. Each member 54 carries a flanged roller 55 which is disposed within the space between the angle irons 27 and 28 and rollable along the track 29. The members 54, bars 53, rollers 52 and 55 together constitute a carriage which is indicated generally by the reference numeral 56.

The carriage 56 is adapted to be reciprocated longitudinally along the machine by the driving means shown at 60 in Fig. 1. The driving means includes an electric motor 61 which drives a speed reduction mechanism 62 through the medium of belts 63. The mechanism 62 includes a rotary crank arm 64 which is connected to oscillate an operating arm 65 by means of a link 66, the arm 65 being pivoted at its lower end as indicated at 67. The upper end of the operating arm 65 is pivotally connected to an axial extension 68 of one of the members 54 by means of a link 69 so that during oscillation of the arm 65, the carriage 56 is reciprocated longitudinally along the rails 35 and 38.

Adapted to reciprocate with the carriage 56 is a primary tucker means 69' which includes a pair of primary tucker elements 70 and 71. The elements 70 and 71 have angular slide portions 72 adapted to slide along the respective support rails 35 and 38, each slide portion having a longitudinally extending leg 73. The forward ends of the legs 73 are connected to upright bars 74 extending upwardly from the bars 53 of the carriage 56 so that upon reciprocation of the carriage, the primary tucker elements 70 and 71 are also reciprocated throughout a portion of the length of the machine. Each element 70 and 71 has a vertical post 75 which carries a plurality of vertically spaced, angular plates 76 each having a forwardly directed finger 77, and is provided with transversely extending edge 78. The edges 78 and fingers 77 of the elements 70 and 71 define between them a recess for receiving the box 16 and the wrapper material 15 which initially encircles the box with its longitudinal edges suitably joined together and with the ends of the wrapper material projecting beyond the ends of the box. Assuming that the primary tucker elements 70 and 71 are disposed at the left-hand or loading end 80 of the machine as shown in Fig. 1, the operator places the box 16, together with the encircling wrapper material 15, in the machine with the opposite ends of the box resting upon the support rails 35 and 38. The operator then slides the box along the rails 35 and 38 and into the recess formed between the elements 70 and 71. By this

procedure, the ends of the box 16 are caused to move into a position between the fingers 77 of the elements 70 and 71. During this movement, the fingers 77 engage the rearward flaps 17 of the wrapper 15 and tuck these flaps forwardly against the ends of the box.

To effect this primary tucking operation, it is necessary that the inner edges of the fingers 77 of the elements 70 and 71 be spaced apart a distance which is substantially equal to the length of the box plus twice the thickness of the wrapper material. Such spacing of the fingers 77 is readily effected by merely turning the handwheel 47 and screw 46 so as to adjust the support rails 35 and 38 toward or away from each other. It is to be noted that during the primary tucking operation, only those fingers 77 which are disposed in alignment with the ends of the box and below the upper surface thereof are utilized for tucking the rearward flaps against the ends of the box, those fingers which are located above the top of the particular box being inoperative. By providing the plurality of vertically spaced fingers 77, boxes of different heights ranging from approximately one-half inch to approximately six inches may be operated upon without adjusting the primary tucker elements vertically to compensate for packages of various heights.

After the package has been placed between the primary tucker elements 70 and 71 and the rearward flaps 17 of the package have thus been tucked, the carriage 56 commences its forward motion. Since the edges 78 of the primary tucker finger plates 76 engage the rearward side of the package, the latter is fed forwardly toward the right-hand or delivery end 81 of the machine. In this manner, the box 16 and its wrapper 15 are advanced to a secondary tucking means which is indicated generally at 85 in Fig. 1.

The secondary tucking means 85 includes a pair of secondary tucker elements 86, each comprising a plurality of vertically spaced bars 87. The bars 87 have longitudinally extending portions 88 and angularly related portions 89 which extend laterally and forwardly from the rearward ends of the portions 88, the intersections of these portions providing corners 90 which are slightly rounded (Fig. 3). During the forward movement of the box and its wrapper, the forward flaps 18 of the wrapper engage the corners 90 of the secondary tucker elements 86 and as the box continues its forward motion with respect to the stationary corners, the forward flaps are tucked inwardly toward the ends of the box 16. As the package is advanced further, the forward and rearward flaps 18 and 17 are retained in their tucked condition by the forwardly extending portions 88.

The bars 87 of the secondary tucker elements 86 are formed integrally with or are secured to vertical plates 92 each of which extends alongside one of the support rails 35 and 38, the rails being reduced in width at this location as indicated at 93 in Fig. 3. The outer ends of the portions 89 of the bars 87 are suitably secured to vertical posts 94. At a suitable distance forwardly of the corners 90, the bars 87 are provided with inclined cam edges 95 (Fig. 3). Forwardly of the cam edges 95, the bars curve downwardly toward the delivery end of the machine, the curved portions 95 of the bars providing primary folder elements of a primary folding means 96 disposed at each side of the machine. As the box and its wrapper are fed forwardly to the secondary tucking means 85, the upper flap 19 at each end of the box enters a space between adjacent bars 87 and as the forward movement of the box is continued, by means to be later described, the flap engages and moves along the lower surface of the curved portion 95 of the bar which overlies the flap so that the latter is deflected downwardly to be folded against the previously tucked flaps 17 and 18. As the box continues its forward motion, the three flaps 17, 18 and 19 at the ends of the box 16 are retained in position against the box by the two plates

92 between which the box is slid to the secondary folding means 100, to be next described.

The secondary folding means 100 consists of a pair of transversely spaced, plate-like switch elements 101 which are disposed within openings 102 cut in the lower portions of the plates 92 forwardly of the primary folding means 96, the plane of each switch element being in alignment with the plane of the corresponding plate 92. The switch elements 101 have pivot lugs 103 adjacent their lower edges, the lugs being pivotally mounted in bearings carried by the plates 92 so as to mount the elements for pivoted movement about a horizontal axis. Each switch element 101 has an edge 105 which curves upwardly and forwardly from its rearward end. The lower edge of each element 101 adjacent its rearward end slopes downwardly and forwardly to provide a cam edge 106. Adjacent each cam edge 106, each support rail 35 and 38 is provided with an opening 107. The switch elements 101 are adapted to be pivoted to either the position shown in Figs. 1 and 4 to 7 or to the position illustrated in Fig. 8 by means of handles 110 carried by the studs 103. The handles 110 are resilient and are thus adapted to snap into either of two notches 111 and 112 formed in the outer edges of flanges 113 of the plates 92.

When the switch members 101 are pivoted to the position shown in Fig. 1, their rearward ends are disposed below the upper surfaces of the support rails 35 and 38. Consequently, as the box is fed forwardly from the primary folding means 96, the bottom flap 20 at each end of the box engages and rides upwardly along the curved surface 105 of a switch element 101, the flap thus being folded upwardly in overlying relation to the flaps 17, 18 and 19, this relation of the flaps being clearly shown in Fig. 10. Following the tucking and folding of the several flaps 17 to 20, the completely wrapped box 16 is fed forwardly along the rails 35 and 38 to the delivery end of the machine and during this latter feeding movement, the flaps of the wrapper may be fused together by heating elements, bonded together by an adhesive applying device or otherwise joined together by any other means, not herein shown.

As thus far described, the machine is adapted to tuck and fold the ends of a wrapper projecting from the ends of an ordinary box. As is well recognized in the art, it is impractical to seal the flaps of a wrapper against the ends of a box in which the edge portions of the top and bottom walls project laterally beyond the side and end walls thereof, such boxes being commonly employed as containers for candy and other articles. In accordance with the present invention, auxiliary folding means are provided for folding the top and bottom flaps 19 and 20 of a wrapper 15, applied to such a box, against the bottom surface of the box to provide what is usually termed a "bottom fold." The auxiliary folding means 120 consists merely of a slot 121 formed in the upper surface of each support rail 35 and 38 (Fig. 3). The slots 121 curve forwardly and inwardly from points adjacent the rearward tip ends of the switch elements 101 and provide curved auxiliary folder edges 122. As shown in Fig. 3, the edges 122 are formed in part by the rearward curved edges of triangularly shaped, lateral projections 123 of the switch elements 101.

To produce a "bottom fold," the switch elements 101 are pivoted to the position shown in Fig. 8 so as to raise their rearward tip ends into the openings 102 of the plates 92 and thus render their curved edges 105 ineffective. At the same time, the rearward ends of the lower inclined edges 106 of the switch elements are disposed above the upper surfaces of the support rails 35 and 38 so that as the box is fed forwardly from the primary folding means 96, the bottom flaps 20 of the wrapper ends engage the inclined edges 106 and are thus deflected downwardly into the curved slots 121 of the auxiliary folding means 120. As the box is fed for-

wardly, the bottom flaps 20, which now extend downwardly, engage the curved edges 122 and are thus folded thereby against the bottom of the box, as shown in Fig. 11. If desired, the top flaps 19 of the wrapper 15 may be made sufficiently long so that when they are folded downwardly by the primary folding means 96, their ends project below the bottom of the box. When such a condition prevails, the ends of the top flaps 19 also enter the curved slots 121 to be folded upwardly against the flaps 20 to complete the "bottom fold." Referring to Figs. 8 and 9, the opening 107, previously mentioned, provides clearance for the flaps 19 and 20 during the folding thereof against the bottom of the box.

Figs. 4 to 8 illustrate the sequence of steps of the complete operation of the machine. For the sake of clarity and simplification, the primary and secondary tucking means and the primary folding means are represented by solid bodies. That is to say, the portions of these means which are disposed below the level of the top flap 19 of the box wrapper are shown as solid walls, rather than composed of a plurality of fingers and bars as in Fig. 1, it being pointed out that all the fingers and bars disposed below these fingers and bars which actually perform a tucking and folding operation cooperate in effecting the wrapping of the box so that all the effective fingers and bars may be regarded as unitary structures. Fig. 4 illustrates the manner in which the rearward flaps 17 of the wrapper are tucked against the ends of the box 16 by the primary tucking means. In Fig. 5, the forward flaps 18 are being tucked against the box by the secondary tucker means. Fig. 6 shows how the top flaps 19 are folded downwardly by the primary folding means and Fig. 7 illustrates the way in which the bottom flaps 20 are folded upwardly by the secondary folding means. As previously pointed out, Fig. 8 indicates the manner in which a bottom fold is produced.

The primary tucking means 69' functions as a primary feeding means to feed the box to be wrapped to the secondary tucking means 85, the forward edges 78 of the tucker elements 70 and 71 engaging the rearward side of the box to push the latter along the rails 35 and 38 during the forward motion of the carriage 56. Simultaneous with the feeding of a box to the secondary tucking means, a box which has been previously fed to the secondary tucking means is advanced successively to the primary and secondary folding means and to the delivery end 81 of the machine by means of a secondary feeding means 130. The secondary feeding means 130 comprises a pair of feeding arms 131 and 132, each of which has its upper forked end 133 pivoted on a pin 134 at the upper end of one of the bars 74 projecting upwardly from the carriage 56 (Figs. 1 and 2). Each feeding arm 131 and 132 normally is directed downwardly by gravity, the upper portion of each arm engaging an inclined stop shoulder to limit its pivotal movement in clockwise direction, as viewed in Fig. 1.

When the carriage 56 is moved forwardly, the primary tucking and feeding means 69' feeds a box from the loading end 80 of the machine to the secondary tucking means. At the same time, the lower ends of the feeding arms 131 and 132 engage the rearward side of a box previously fed to the secondary tucking means so as to feed this box to the primary and secondary folding means (or to the auxiliary folding means) and to the delivery end 81 of the machine. As the motion of the reciprocating carriage is reversed, the primary tucking means 69' is returned to the loading end 80 of the machine to receive another box to be wrapped, and the feeding arms 131 and 132 are moved rearwardly to the position shown in Fig. 1 in readiness to perform another secondary feeding operation. During the return movement of the carriage 56 the arms 131 and 132 ride over the top of the box which has been fed to the secondary tucking means 85, the arms pivoting forwardly on their pins 134 to permit such movement. After the lower ends of the arms

131 and 132 clear the rearward side of the box, they swing downwardly to the operative position shown in Fig. 1. It is thus seen that the present semi-automatic wrapping machine operates upon two boxes during each forward stroke of the carriage so that the boxes to be wrapped are fed through the entire machine in response to a relatively short reciprocatory movement of the feeding means.

While the improved wrapping machine has been described herein as embodied in a preferred form of construction, by way of example, it will be apparent that various modifications might be made in the construction of the machine without departing from the spirit of the invention. Consequently, I do not wish to be limited in this respect, but desire to be afforded the full scope of the appended claims.

I claim as my invention:

1. In a package wrapping machine, the combination of: a frame providing a longitudinal support upon which a package having a foldable wrapper encircling the package can be placed with the open ends of the wrapper projecting from opposite ends of the package transversely of said support; a pair of primary tucker means movable longitudinally along said support and spaced transversely thereof, said tucker means including tucking fingers directed toward each other with their facing sides spaced apart a distance substantially equal to the length of the package to be wrapped and adapted to tuck the rearward vertical flaps of the wrapper ends inwardly against the ends of the package upon movement of the package into position between said fingers; feeding means operative to advance said package along said support; a pair of secondary tucker means extending alongside said support and engageable with the forward vertical flaps of the open ends of the wrapper of the forwardly advancing package so as to tuck the same inwardly against the ends of the package; a pair of transversely spaced primary folding means including lower folder edges sloping downwardly in the direction of movement of the package and adapted to engage and fold the upper flaps of said open ends of the wrapper downwardly in overlying relation to the tucked forward and rearward flaps, upon relative movement between said primary folding means and said package; a pair of secondary transversely spaced, folding means defining cam edges disposed in advance of said folder edges and sloping upwardly in the direction of movement of the package, said cam edges being adapted to engage the lower flaps of the wrapper ends during advancement thereof, relative movement between said package and said cam edges effecting upward folding of said lower flaps in overlying relation to the previously tucked forward and rearward flaps and the previously folded upper flaps of the wrapper ends, said secondary folding means including a pair of plates each having a said cam edge, each plate being movable with respect to said support to a first position in which the end of its cam edge disposed nearest said primary folding means is located in the plane of said bottom flap of said wrapper, and to a second position in which said end of its cam edge is disposed out of the plane of said bottom flap; and means cooperating with said plates when in said second position for folding said lower flaps to a different position than upwardly.

2. The combination defined in claim 1 in which said pair of plates each having a said cam edge, is each pivotally mounted on said support.

3. The combination defined in claim 1 in which said secondary folding means pair of plates are vertical, transversely spaced and each has an upper curved edge providing said cam edge and a lower deflector edge sloping downwardly in the direction of feed of the package, each of said plates being adapted to pivot on a horizontal axis with respect to said support to a first position in which the end of its curved cam edge disposed nearest

said primary folding means is located in the plane of said bottom flap of said wrapper so as to fold said bottom flap upwardly, and in which the end of its deflector edge disposed nearest said primary folding means is located below the plane of said bottom flap, each of said plates being adapted to pivot to a second position in which the end of said cam edge disposed nearest said primary folding means is located above the plane of said bottom flap and the end of said deflector edge disposed nearest said primary folding means is located substantially in the plane of said bottom flap, in which case said deflector edge is engageable with and operative to deflect said bottom flap downwardly.

4. The combination defined in claim 3 in which said support has a pair of auxiliary folder means each including a transversely spaced, curved slot extending inwardly and in the direction of feed of the package from a point adjacent the juncture of said cam edge and said deflector edge of one of said plates, said slots being adapted to receive the bottom flaps of said wrapper ends deflected downwardly by said deflector edges and to fold the same inwardly against the bottom of the package during travel of the package across said slots.

5. The combination defined in claim 3 in which said machine has a pair of auxiliary folder means each including a bottom fold edge disposed substantially in the plane of the bottom of the package and extending inwardly and in the direction of feed of the package from a point adjacent the juncture of said cam edge and said deflector edge of one of said plates, said bottom fold edge being adapted to engage the top and bottom flaps of a said wrapper end deflected downwardly by a said deflector edge and to fold the same against the bottom of the package during travel of the package across said bottom fold edge.

6. In a wrapping machine for a package having a foldable wrapper encircling the package with the open ends of the wrapper projecting from opposite ends of the package, the combination of primary tucker means for tucking the rear vertical flaps of the wrapper ends inwardly against the ends of the package; secondary tucker means for tucking the forward vertical flaps of the open ends of the wrapper inwardly against the ends of the package; primary folding means for engaging and folding the upper flaps of the open ends of the wrapper downwardly and in overlying relation to the tucked forward and rearward end flaps; secondary folding means for engaging and folding the lower flaps of the open ends of the wrapper upwardly and in overlying relation to the folded upper flaps; alternative secondary folding means for engaging and folding the lower flaps of the open ends of the wrapper downwardly and beneath the package and simultaneously engaging and folding underneath the package that portion of the downwardly folded upper flaps which extend below the package; and a pair of switching plates having curved upper edges and disposed in positions corresponding to the opposite ends of said package and each movable to different positions, in one of which the upper edges of said plates form at least a portion of said secondary folding means and in another of which said lower flap is guided into engagement with said alternative secondary folding means.

7. In a wrapping machine for a package having a foldable wrapper encircling the package with the open ends of the wrapper projecting from the opposite ends of the package, said machine including means for tucking the vertical flaps of said wrapper ends inwardly toward said package, means for folding the upper flaps of said wrapper downwardly toward said package, means for folding the lower flaps of said wrapper upwardly toward the package or downwardly underneath said package and means for effecting a relative movement between said package and said tucking and folding means, the improvement which comprises a plurality of parallel bars at each side of the relative path of movement, extending opposite to

the direction of relative movement, and spaced apart in a direction perpendicular thereto, for tucking the forward flaps of said wrapper ends inwardly toward said package; and means defining a plurality of cam edges extending in a direction to fold the upper flaps of said wrapper ends against said package, said bars guiding said upper flaps to said cam edges.

8. In a wrapping machine, the improvement defined in claim 7, including a plate disposed at each side of the path of relative movement and provided with a plurality of slots defining said cam edges, said plates being parallel and adjacent said bars and said slots having widths equivalent to the spaces between said bars.

9. In a wrapping machine for a package having a foldable wrapper encircling the package with the open ends of the wrapper projecting from the opposite ends of the package, said machine including means for tucking the vertical flaps of said wrapper ends inwardly toward said package, means for folding the upper flaps of said wrapper downwardly toward said package, means for folding the lower flaps of said wrapper upwardly toward the package or downwardly underneath said package, and means for effecting a relative movement between said package and said tucking and folding means, the improvement which comprises a plurality of parallel fingers in sets at each side of the path of relative movement, extending in the direction of relative movement, and spaced apart in a direction perpendicular thereto, for tucking the rear vertical flaps of said wrapper ends inwardly against said package; a plurality of parallel bars in sets at each side of the path of relative movement, extending in a direction opposite to the direction of relative movement, and spaced apart in a direction perpendicular thereto and substantially the same distances as said fingers, for tucking the forward vertical flaps of said wrapper ends inwardly against said package; and means for moving said fingers in unison toward and away from said bars, between a first position in which said finger sets are spaced from said bar sets and a second position in which at least a portion of said fingers are alongside said bars, at least a portion of said fingers being relatively narrow and said finger sets being spaced apart a distance equivalent to the length of said package, and the portions of said bars of said sets alongside said fingers in said second position being spaced apart a distance to permit said fingers to move alongside the same, said bars of each set then converging toward the opposite set until the distance between the bars of said sets approximates the length of said package.

10. In a wrapping machine for a package having a foldable wrapper encircling the package with the open ends of the wrapper projecting from the opposite ends of the package, said machine including means for tucking the vertical flaps of said wrapper ends inwardly toward said package, means for folding the upper flaps of said wrapper downwardly toward said package, means for folding the lower flaps of said wrapper upwardly toward the package or downwardly underneath said package, and means for effecting a relative movement between said package and said tucking and folding means, the improvement which comprises a pair of parallel, spaced rails adjustable toward and away from each other and extending in the direction of relative movement, said tucking means being mounted on said rails said means for

folding said upper flaps being mounted on said rails forwardly of said tucking means, said rails being wider at the positions at which said tucking and upper flap folding means are mounted, said rails then being narrower with the outer edges of said rails being spaced apart a distance equivalent to the length of said package; and means co-operating with said outer edges for folding said lower flaps underneath said package.

11. In a package wrapping machine, the combination of: a frame providing a longitudinal support upon which a package having a foldable wrapper encircling the package can be placed with the open ends of the wrapper projecting from the opposite ends of the package transversely of said support; a pair of primary tucker means movable longitudinally along said support and spaced transversely thereof, said tucker means including a slide element and a plurality of tucking fingers carried by said slide and disposed in vertically spaced relationship at opposite sides of said slide, said tucking fingers at said opposite sides being directed toward each other with their facing sides spaced apart a distance substantially equal to the length of the package to be wrapped and adapted to tuck the rearward vertical flaps of the wrapper ends inwardly against the ends of the package upon movement of the package into position between said fingers; a pair of secondary tucker means including a plurality of vertically spaced bars extending alongside said support and engageable with the forward vertical flaps of the open ends of the wrapper of the forwardly advancing package so as to tuck the same inwardly against the ends of the package; a pair of normally stationary, spaced, primary, folding means including lower folder edges formed by a plurality of vertically spaced bars generally coextensive with said bars of said secondary tucker means and sloping downwardly in the direction of movement of the package and adapted to engage and fold the upper flaps of said open ends of the wrapper downwardly in overlying relation to the tucked forward and rearward flaps, upon relative movement between said primary folding means and said package; a pair of normally stationary, secondary, transversely spaced, folding means defining cam edges disposed in advance of said folder edges and sloping upwardly in the direction of movement of the package, said cam edges being adapted to engage the lower flaps of the wrapper ends during advancement thereof, relative movement between said package and said cam edges effecting upward folding of said lower flaps in overlying relation to the previously tucked forward and rearward flaps and the previously folded upper flaps of the wrapper ends; said primary tucker means providing a primary feeding means for moving the package a portion of the length of said support; and a secondary feeding means engageable with the rearward side of a previously advanced package and operative to advance the package throughout the remainder of its necessary travel through the machine.
